UNITED STATES PATENT OFFICE.

CÆSAR A. CUPPIA, OF NEW YORK, N. Y.

DESIGN FOR A KNOB FOR VESSELS.

SPECIFICATION forming part of Design No. 28,260, dated February 8, 1898.

Application filed November 20, 1897. Serial No. 659,338. Term of patent 3½ years.

To all whom it may concern:

It is known that I, CÆSAR A. CUPPIA, a citizen of the United States, residing at New York city, in the county and State of New York, have invented and produced a new and original Design for Knobs for Vessels, of which the following is a specification, reference being had to the accompanying drawings, forming a part thereof, in which—

10 Figure 1 is a plan view of a knob for vessels embodying the features of my design, and Fig. 2 is a side elevation of the same.

15 The leading feature of the design consists in a stag-crown A and the shank B for the crown.

A further feature of the design consists in the formation of the shank, which is reduced relatively to the crown, and in the configuration of the back of the crown, which is roughened to simulate the exterior surface of a stag-horn.

I claim—

The design for a knob for vessels, herein shown and described.

CÆSAR A. CUPPIA.
